UNITED STATES PATENT OFFICE

JAMES HENRY REID, OF NEWARK, NEW JERSEY, ASSIGNOR, BY MESNE ASSIGNMENTS,
TO THE PATENTS PURCHASING COMPANY, OF APPLETON, WISCONSIN, A CORPORA-
TION OF WISCONSIN.

ELECTRIC REFINING-CRUCIBLE.

1,026,281.

Specification of Letters Patent.

Patented May 14, 1912.

Application filed July 19, 1911. Serial No. 639,469.

To all whom it may concern:

Be it known that I, JAMES HENRY REID, a citizen of the United States, residing at 352 Mulberry avenue, in the city of Newark, 5 State of New Jersey, United States of America, have invented certain new and useful Improvements in Electric Refining-Crucibles, of which the following is a specification.

My invention relates to improvements in 10 electric refining crucibles and the objects of the invention are to facilitate the initial heating of the crucible and avoid the necessity of using an excessive amount of current to effect the heating and it consists essentially of current conducting elements operative 15 in recesses in the wall of the crucible in the manner hereinafter more fully set forth and described in the accompanying specification and drawings.

20 In the drawings: Figure 1 is a sectional view through a crucible embodying the present invention. Fig. 2 is a section on the line 2—2 Fig. 1.

25 Referring to the drawings A represents a crucible of any usual or desirable shape and preferably formed of refractory material such as dolomite or magnesite. The crucible may if desired be mounted with freedom of rotation in the manner, for example shown 30 and described in my United States Patent No. 920391 dated May 4th, 1909. As illustrated herein however, the crucible is stationary and is supplied with current from conducting rings 10 and 11 at the top and bottom 35 thereof.

Following the present invention, the side walls of the crucible are formed with recesses 12 and 13 extending from the top to near the bottom, and adapted to contain current 40 conducting elements B and C which are slidable therein and adjusted by suitable means such as the adjusting screws 14 connected thereto and extending through side brackets 15 on the crucible. If desired those 45 recesses might communicate with the interior of the crucible. A current conducting element D, is also provided adapted to be moved into contact with the bottom and shaped to conform to the bottom and extending across nearly 50 the full width thereof. This member is connected in parallel with the ring 11, and is adapted to be moved into and out of engagement by suitable means, such as the screw 17 through the plate 18.

It will be seen that when the current conducting elements B and C are in innermost position, the conductivity of the sides will be very much increased. This will be further facilitated by moving the element D into engagement with the bottom. After 60 the crucible is once heated the current conducting elements may be withdrawn and the current passed wholly through the crucible itself. The withdrawal of the elements might be effected automatically by means 65 controlled by temperature of the crucible in a manner similar to that described for electrode regulation in my co-pending application Serial No. 640345, filed July 24/11. With regard to the starting of the operation it 70 may be explained that the material in the crucible will be in a molten state, and will therefore heat the crucible sufficiently to render it conductive. In the case of the form in which the recesses 12 are connected 75 with the interior of the crucible, the operation may readily be started when the crucible is cold.

As many changes could be made in the above construction and many apparently 80 widely different embodiments of my invention, within the scope of the claims, constructed without departing from the spirit or scope thereof, it is intended that all matter contained in the accompanying specification 85 and drawings shall be interpreted as illustrative and not in a limiting sense.

What I claim as my invention is:

1. An electric refining crucible having means for varying the conductivity of the 90 walls thereof during the operation of the furnace.

2. An electric refining crucible formed of material only possessing conductivity when heated and having means for reducing the 95 conductivity of the crucible as the operation proceeds.

3. An electric refining crucible having a second class current conducting wall and a 100 conducting element, contacting with the same and adapted to be moved into positions to increase the conductivity of the sides.

4. An electric refining crucible having a recessed current conducting wall, a current 105 conducting element movable therein and means for moving the current conducting element inwardly and outwardly.

5. An electric refining crucible of refrac-

tory material having recesses extending down the walls and current conducting elements movable in the recess.

6. An electric refining crucible having recessed walls and current connections at the top and bottom of the walls, current conducting members in the recesses, and a current contacting member movable into engagement with the bottom of the crucible and con-

nected in parallel with the bottom current connection.

In witness whereof I have hereunto set my hand in the presence of two witnesses.

JAMES HENRY REID.
